FIG. 3

UNITED STATES PATENT OFFICE.

GEORGE E. MUSEBECK, OF MILWAUKEE, WISCONSIN, ASSIGNEE OF ONE-FOURTH TO
GEORGE E. MUSEBECK, ONE-FOURTH TO RICHARD JENNINGS, ONE-FOURTH TO
CHARLES W. CONAWAY, AND ONE-FOURTH TO WALTER A. WADSWORTH, ALL OF
MILWAUKEE, WISCONSIN.

VAMP-FORMING MACHINE.

Application filed July 23, 1919. Serial No. 312,776.

To all whom it may concern:

Be it known that I, GEORGE E. MUSEBECK, a citizen of the United States, and resident of Milwaukee, in the county of Milwaukee, and State of Wisconsin, have invented new and useful Improvements in Vamp-Forming Machines, of which the following is a description, reference being had to the accompanying drawings, which are a part of this specification.

The invention relates to a vamp-forming machine for shoes and has for its object to produce a vamp having a molded or set throat portion which is shaped to substantially conform to the shape of the last so that the usual stretching and forming of the vamp over the last with its consequent disadvantages are obviated.

The further object of the invention is to provide a vamp-forming machine in which pressure is gradually applied to the throat portion of the vamp to form it to the desired shape.

A further object of the invention is to provide means for heating the vamp during the forming operation.

The invention further consists in the several features hereinafter set forth and more particularly defined by claims at the conclusion hereof.

In the drawings Fig. 1 is a side view of the machine embodying the invention, parts being broken away and parts being shown in section; Fig. 2 is a plan view thereof; Fig. 3 is a section taken on the line 3-3 of Fig. 2.

The numeral 4 designates the frame of the machine having uprights 5 and 6 in which shafts 7 and 8 are journaled. The shaft 7 is the drive shaft and carries a loose pulley 9, a fixed pulley 10 and a fly wheel 11, and a belt (not shown) is connected to any suitable source of power and when shifted to the pulley 10 rotates the shaft 7.

The shaft 8 is mounted in a swinging or oscillating frame 12 and intermediate the ends thereof. This frame has a slotted rear end 13 provided with guideways 14 in which a two part block 15 is slidably mounted. The cranked or eccentric portion 16 of the shaft 7 is journaled in said block. The wear on the bearing block 15 and its frictional engagement with the guideways 14 is adjusted by bolts 17 which pass through the end 13

of the frame on opposite sides of said block.

A die 20 has its base removably held in a pocket formed by side strips 21 and an end strip 22 fixed to the frame 4 and an end strip 23 removably secured to the frame 4 by screws 24. The sides 25 of the die are inclined and at their lower edges fit in the guideways 26 formed by the inwardly beveled edges of the strips 21. This die 20 has a vamp-forming recess 27 therein of semi-conoidal shape in which the curvature of successive sections gradually increases from the forward end 28 to the rear end 29 of said recess, Fig. 3 showing in dotted line a section taken on the line 4-4 of Fig. 2.

The outer end 30 of the frame 12 has a vertically disposed bore 31 in which a threaded spindle 32 is adjustably mounted. This spindle has a head 33 at its lower end provided with a bore 34 and a die 35 has a stem 36 seated in said bore 34 and secured to said head by a set screw 37, though it is to be understood that other means may be employed to clamp or secure the die to said spindle.

This die 35 is the counterpart of the die 20 and cooperates therewith to shape the throat portion of the vamp as it is introduced between them.

For accommodating the machine to vamp blanks of different thicknesses of leather the spindle is slidably but non-rotatably adjustable in the frame 12 by means of a spline 38 in said spindle, a screw 39 mounted in the frame and having its inner end slidably engaging the spline 38 to prevent rotation of the spindle, a feed nut 40 in threaded engagement with the upper end of the spindle and the lock nut 41 in threaded engagement with the spindle below the bore 31. With this construction, on a loosening up of the nut 41 the spindle may be raised or lowered to adjust the distance of the die 35 from the die 20 by rotating the nut 40 and the spindle is then locked in adjusted position by tightening up the nut 41 against the frame 12.

In order to heat the vamp during the forming operation I have provided means for heating the movable die 35 by means of a gas jet issuing from a gas supply pipe 42 and directed into a heating chamber 43 in said die, though it will be understood that

other forms of heating arrangements may be used, as an electric heating coil, if desired.

With the construction above described the frame 12 is preferably oscillated quite rapidly by rotating the shaft 8 at a fair rate of speed. As said frame 12 oscillates the dies 35 and 20 are moved toward and away from each other, during which time the throat portion of the vamp blank is gradually fed inwardly between the dies and formed into shape to substantially conform to the shape of the last and preferably under the application of heat, as by imparting heat to the blank by heating one of the dies in the manner above described.

The forming faces of the dies 35 and 20 are preferably so shaped that pressure upon the blank is localized to the throat portion only. This has the advantage of preventing tearing or splitting of the vamp where the throat portion meets the wings, of preventing distortion of the forward portion and wings of the vamp to avoid trimming.

I desire it to be understood that this in-

vention is not limited to any specific form or arrangement of parts except in so far as such limitations are specified in the claims.

What I claim as new and desire to secure by Letters Patent is:

1. In a vamp-forming machine, the combination of a support having a die mounted thereon, an oscillatory frame carried by said support, means for oscillating said frame, and a die fixed to said frame and cooperating with said first named die to shape the throat portion of the vamp from a vamp blank during successive oscillations of said frame. 30

2. In a vamp-forming machine, the combination of a support having a die mounted thereon, an oscillatory frame carried by said support, means for oscillating said frame, a die carried by said frame and cooperating with said first named die to shape the throat portion of the vamp blank, and means for adjusting the spacing of the dies with respect to each other. 40

In testimony whereof, I affix my signature.

GEORGE E. MUSEBECK.
